UNITED STATES PATENT OFFICE.

WILLIAM M. DEHN, OF SEATTLE, WASHINGTON.

PROCESS OF MANUFACTURING ADHESIVE BLENDS OF SODIUM NITRATE AND AMMONIUM NITRATE FOR EXPLOSIVE PURPOSES.

No Drawing.

Application filed October 13, 1924. Serial No. 743,1694.

To all whom it may concern:

Be it known that I, WILLIAM M. DEHN, a citizen of the United States, residing at Seattle, county of King, and State of Washington, have invented a certain new and useful Process of Manufacturing Adhesive Blends of Sodium Nitrate and Ammonium Nitrate for Explosive Purposes, of which the following is a full, clear, and exact description.

My invention relates to the process, and the product of the process, of manufacturing blends of sodium nitrate and ammonium nitrate wherein, in general, the particles of sodium nitrate have adhering to them substantially equal or lesser masses of ammonium nitrate. This condition of intimate and adhesive contact of the two salts, during the explosion of compositions of which they are ingredients, promotes a mutual and beneficial effect not obtainable to the same degree, when the two independent salts are mingled mechanically in powders.

The chief object of my invention is to obtain very inexpensive powders especially adaptable to conditions of stump-blasting and the like.

It is well known that when independently powdered sodium nitrate and ammonium nitrate are added to wood meal, the compositions thus obtained are practically worthless as blasting powders. I have found that when liquid nitrotoluenes, so low in concentration as 5%, are added to these compositions, other compositions are obtained that are also practically worthless. However, on the other hand, I have found that when the two salts are first powdered and then are wholly or partly melted together, and the blended mass thus obtained is cooled and re-powdered, I can mix it with wood meal and 5% of nitrotoluene so as to obtain readily detonating compositions.

The enhanced explosive properties of such blends of the nitrates of sodium and ammonium, therefore, not only is demonstrated but can be accounted for by the following observations. On the one hand, it is well known that powdered sodium nitrate in explosive compositions is very likely, during combustion and detonation, to melt and segregate in drops of such size that detonation is retarded or is prevented. Owing to this tendency, compositions of sodium nitrate, containing an insufficient sensitizing com-

ponent, tend to burn without detonating and the charge may be lost in this manner in the blast hole. Furthermore, on account of its high thermal and oxidizing effects in compositions of which it is an ingredient, sodium nitrate contributes a dangerous hazard to manufacture and storage. On the other hand, during combustion and detonation, ammonium nitrate evolves gases, shows little or no tendency to melt and segregate, and exerts an inhibitory effect on simple combustion. Furthermore, like sodium nitrate, it is an oxidant, but, unlike sodium nitrate, it itself is a powerfully detonating material.

Now when these two nitrates are combined in minute and intimate contact, as set forth in this specification, so that their independent kindling and detonating properties are mingled, beneficial explosive effects are obtained. This can be demonstrated as described above or by measurements in the sand bomb or by the mere heating of their mixtures—the melted mass is observed to froth and foam and thus the ammonium nitrate counteracts a tendency of sodium nitrate to fuse into compact masses. Furthermore, the blends and its mingled compositions are found to differ from simple mixtures in density, by hygroscopy and ease of ignition.

The novelty of my invention resides in the process whereby I combine the two nitrates so as to avoid the objectionable kindling properties of the sodium nitrate and to secure enhanced explosive properties in compositions in which they are ingredients. There advantages are secured by bringing the two nitrates into minute, intimate and adhesive contact through melting.

It is well known that certain mixtures of the two salts melt at lower temperatures than the melting temperature of either of the two salts and that an eutectic point is found at or about 120° C. for the mixture containing four parts of ammonium nitrate and one part of sodium nitrate. At 170° C., which is above its melting point, the ammonium nitrate forms the preponderating component of all fused mixtures of the two salts. Furthermore, since ammonium nitrate begins to decompose at temperatures even lower than its melting point (169.6° C.), it is evident that a 50—50 percentage composition of the two salts, or mixtures containing

a preponderating mass of sodium nitrate, cannot be formed by simply melting. However, I have found that blends of the two salts, approximating in minuteness and intimacy of contact of the completely fused mixtures, can be manufactured by the herein disclosed process.

For example, to manufacture a blend containing these salts in equal weight, I take 10 parts of dry powdered ammonium nitrate and one part of dry powdered sodium nitrate and melt them as completely as possible at a temperature substantially not to exceed 160° C., then I add one other part of 15 the sodium nitrate to the fused mass and, while stirring, bring the temperature substantially to 160° C. The sludge thus formed is cooled as rapidly as possible, for example, by pouring in thin layers onto concrete or metal slabs. The hard cooled mass is next ground to a powder and is incorporated at once with the other ingredients of the explosive composition. In preparing this blend the preponderating mass of the 20 sodium nitrate, in a state of minute subdivision, is imbedded in a matrix of the two salts which had been melted and quickly cooled. When the cool mass, which is substantially an öölitic conglomerate, is ground to a powder, or when this powder is remelted and repowdered, each particle, or substantially each particle, is observed under the microscope to contain both of the nitrates in intimate and adhesive contact. 25 The effect of this minuteness and intimacy is that ammonium nitrate gives off gas at such a rate that segregation by melting of the particles of sodium nitrate is prevented, in other words, besides yielding oxygen and explosive power, the ammonium nitrate functions as an atomizing agent for sodium nitrate during the moment of detonation, giving rise to intermingling of gaseous and liquid phases and producing frothing and foaming effects which accelerate the explosion. Further advantages obtained by this process of blending are insensitiveness towards simple combustion and progressiveness of explosion.

30 Experiments with water added to the salts to increase their fusibility yielded masses that were difficult to dry and were hopelessly insensitive towards detonation, hence the necessity of fusing only dry powdered salt was demonstrated. Other experiments, wherein the salts were heated long at temperatures above 160° C., yielded inferior products, hence the lower favorable range of temperatures, substantially 125 to 35 160° C., was demonstrated. When the melted mixtures were permitted to cool slowly or in thick layers, undesirably large interior crystals formed, hence the necessity of rapid solidification either by chilling, by spraying, or by pouring in thin layer, was

demonstrated. When blends containing very largely preponderating masses of sodium nitrate are to be manufactured, as for example, when four parts of sodium nitrate are combined with one part of ammonium nitrate, the sludges obtained must be stirred strongly while pouring onto the cooling slabs, in order to prevent settling of the unmelted component.

As an example of an explosive manufactured from the blends of nitrates, herein described, I can take a 50-50 percentage powdered blend and add to it first liquid nitrotoluene and then wood meal so that the percentages of composition will be as follows:

A—	Sodium nitrate	38
	Ammonium nitrate	38
	Wood meal	19
	Nitrotoluene	5

This powder was found to be of good density for loading of cartridges and was very effective in stump blasting.

Other effective compositions can be prepared in the following percentages of composition:

	B	C	D
Sodium nitrate	50	54	54
Ammonium nitrate	25	26	18
Wood meal	20	10	18
Nitroglycerine	5	—	—
T N T	—	10	—
Wood meal impregnated with ammonium nitrate	—	—	10

From these examples, it is clear, that a great variety of explosive compositions can be manufactured from the blended salts. In general, all nitro organic compounds commonly used in powders, also wood meal impregnated with ammonium nitrate by my prior process (U. S. Pat. No. 1,444,594), can be used to sensitize mixtures of the blends present with combustibles such as wood meal, charcoal, starch, etc.

All of these compositions, involving as they do the manufacture of the blend by the herein disclosed process and the blend itself as an ingredient thereof, are held to fall within the scope of my claims.

I claim:

1. The process of manufacturing conglomerate masses of ammonium nitrate and sodium nitrate for explosive purposes, which comprises changing by application of heat mixtures of said salts to sludges and then cooling rapidly to uniform conglomerates which are to be pulverized.

2. The process of manufacturing conglomerate masses of ammonium nitrate and sodium nitrate for explosive purposes, which comprises the partial melting of their mixtures and the rapid cooling and pulverizing of the product thereof.

3. The process of manufacturing con-

glomerate masses of ammonium nitrate and sodium nitrate for explosive purposes, which comprises applying heat throughout their mixtures so as to obtain practically 5 the maximum melting of said mixtures without substantial decomposition of ammonium nitrate.

4. The process of manufacturing cölitic conglomerates of ammonium nitrate and sodium nitrate for explosive purposes which comprises melting mixtures of the two powdered salts in the presence of a further and preponderating mass of sodium nitrate too great to be melted at the temperature used. 10 5. The process of manufacturing adhesive blends of ammonium nitrate and sodium nitrate for explosive purposes which comprises heating mixtures of the dry powdered nitrates so as to obtain substantially 15 the greatest fluidity of the sludge and then stirring and cooling so as to obtain substantially uniform conglomerates.

6. The process of manufacturing adhesive blends of ammonium nitrate and sodium nitrate for explosive purposes which comprises melting all of the ammonium nitrate and part of the sodium nitrate while the preponderating mass of sodium nitrate is present in a state of fine subdivision, so 20 that subsequent rapid cooling will incorporate the unmelted powdered sodium nitrate in a matrix of the two fused salts.

7. The process of manufacturing adhesive blends of ammonium nitrate and sodium nitrate for explosive purposes which comprises heating mixtures of said salts at 125-160° C., rapidly cooling its sludge and powdering its conglomerate thus formed.

8. The process of manufacturing adhesive blends of ammonium nitrate and sodium nitrate for explosive purposes which comprises heating mixtures of the dry pulverized nitrates at 125-160° C., then stirring and pouring onto cooling slabs in thin layers, so that rapid cooling of the sludges will substantially prevent the formation in the conglomerates of large interior crystals.

9. The process of manufacturing adhesive blends of ammonium nitrate and sodium nitrate for explosive purposes which comprises heating mixtures of 4-1 parts of pulverized ammonium nitrate with 1-4 parts of dry pulverized sodium nitrate at 125-160° C. so as to obtain substantially the maximum possible fusion of the two salts, then, while stirring so as to prevent settling of the unmelted sodium nitrate, pouring rapidly in thin layers onto cooling slabs so as to obtain rapid cooling, and finally pulverizing the conglomerate masses thus formed.

10. The process of manufacturing adhesive blends of ammonium nitrate and so-

dium nitrate for explosive purposes, which 65 comprises heating, cooling and pulverizing the salts, substantially as described, and then repeating the heating, cooling and pulverizing.

11. As an ingredient for explosive purposes, eutectic mixtures of ammonium nitrate and sodium nitrate, manufactured substantially as described. 70

12. As an ingredient for explosive purposes, adhesive blends of ammonium nitrate and sodium nitrate, manufactured substantially as described. 75

13. As an ingredient for explosive purposes, minute particles of unmelted sodium nitrate adhering to minute particles composed of melted mixtures of ammonium nitrate and sodium nitrate, manufactured substantially as described. 80

14. As an ingredient for explosive purposes, adhesive blends of ammonium nitrate and sodium nitrate, manufactured as described and possessing explosive properties substantially different from mere mechanical mixtures of the same. 85

15. As an ingredient for explosive purposes, adhesive blends of ammonium nitrate and sodium nitrate, manufactured by melting mixtures of the dry powdered salts, in the presence of a preponderating mass of unmelted sodium nitrate, by cooling rapidly so as to form an uniform conglomerate of the materials, and by pulverizing. 90

16. As an ingredient for explosive compositions, adhesive blends of ammonium nitrate and sodium nitrate, manufactured by melting at 125-160° C. mixtures of the dry powdered salts, in the presence of a preponderating mass of unmelted sodium nitrate, by cooling rapidly so as to form an uniform conglomerate of the materials, and by pulverizing. 105

17. As an ingredient for explosive compositions, adhesive blends of ammonium nitrate and sodium nitrate, manufactured by melting at 125-160° C., 4-1 parts of ammonium nitrate and 1-4 parts of sodium nitrate, by cooling rapidly so as to form a uniform conglomerate of the materials, and by pulverizing. 110

18. As an ingredient for explosive compositions, adhesive blends of ammonium nitrate and sodium nitrate, manufactured by melting at 125-160° C., 4-1 parts of ammonium nitrate and 1-4 parts of sodium nitrate, by cooling rapidly so as to form a uniform conglomerate of the materials, and by pulverizing, the product thus formed to be remelted at 125-160° C., rapidly cooled and repowdered. 120

In testimony that I claim the foregoing, I hereto set my hand, this 8th day of October, 1924. 125

WILLIAM M. DEHN.
